LIGHT FIXTURE

Elsie Crawford, 1930 Waverly, Palo Alto, Calif.

Filed Oct. 23, 1964, Ser. No. 82,289

Term of patent 7 years

(Cl. D48—23)

FIG. 1

FIG. 2

FIG. 3

FIG. 4

FIG. 5

FIG. 1 is a perspective view of the light fixture embodying my new design.

FIG. 2 is a top plan thereof with portions omitted for convenience of illustration only.

FIG. 3 is a bottom view.

FIG. 4 is a side elevation view.

FIG. 5 is an end elevation view.

The opposite side elevation view is the same as the elevation view shown in FIG. 4.

The opposite end elevation view is the same as the end elevation view shown in FIG. 5.

I claim:

The ornamental design for a light fixture, substantially as shown and described.
